UNITED STATES PATENT OFFICE.

GOODRICH Q. LEWIS, OF WHEATON, ILLINOIS, ASSIGNOR TO WILLIAM H. MINER, OF CHAZY, NEW YORK.

RAILWAY-CAR DRAFT-RIGGING.

1,293,131.

Specification of Letters Patent.

Patented Feb. 4, 1919.

Application filed July 13, 1916. Serial No. 109,002.

To all whom it may concern:

Be it known that I, GOODRICH Q. LEWIS, a citizen of the United States, residing at Wheaton, in the county of DuPage and State of Illinois, have invented a certain new and useful Improvement in Railway-Car Draft-Rigging, of which the following is a full, clear, concise, and exact description, reference being had to the accompanying drawings, forming a part of this specification.

This invention relates to improvements in railway car draft riggings.

The object of the invention is to provide a draft rigging for railway cars so arranged that all the buffing and pulling strains are transmitted to the car under-frame at points in the rear of the gear and adjacent the body bolster.

In the drawing forming a part of this specification, Figure 1 is a part side elevation, part vertical, longitudinal section of a draft rigging showing my improvements in connection therewith. And Fig. 2 is a horizontal, sectional view of the structure illustrated in Fig. 1, the section being taken above the gear and below the top sill plate, except at the forward end where the section is lower to illustrate the slots for the coupler key.

In said drawing, 10-10 denote channel shaped, center sills spaced the usual distance apart and extending between and rigidly connected thereto is an abutment block or casting 11. The latter comprises a vertical front face 12, top wall 13, intermediate wall 14, bottom wall 15, and side walls 16-16, the latter being directly riveted to the sills. In the drawing is illustrated a friction gear of a well known type, the same comprising a spring cage 17 and friction shell 18 integrally formed, the friction shell being extended toward the rear. Mounted within the spring cage are twin springs 19 and within the friction shell are the usual friction shoes 20, wedge 21, anti-friction rollers 22 and preliminary spring 23. The wedge engages a rear follower 24 which is resisted from rearward movement by the block 11, the rear end of a horizontal yoke 25 being interposed between said follower and said block. The arms of the yoke 25 are slotted at their forward ends to receive a coupler key 26 by which the yoke is connected to a draw bar 27, the latter directly abutting the front end of the spring cage 17. On the top

and bottom thereof, the combined spring cage and friction cylinder is provided with a substantially T-shaped slot or recess 28 in which are adapted to be seated T-shaped front ends 29 of two links 30-30. The links 30 are each provided with elongated slots 31 at their rear ends to accommodate a vertical, heavy pin 32 which passes through alined perforations in the walls 13, 14 and 15 of the block 11. The links 30-30 are preferably reinforced, as indicated at 33, around the slots. As clearly shown in the drawing, the spring cage is provided with flanges 34-34 which over-lap the extreme front ends of the T-heads 29 and thus prevent the latter from being displaced when the parts are assembled. A tie plate 35 is provided to support the gear proper and the yoke 25 is supported by means of angle irons 36-36 secured to the inner faces of the sills, said angle irons being so disposed that their horizontal flanges are uppermost and thus form supports for the yoke. The pin 32 is detachably held in position by means of another tie plate 37 secured to the lower flanges of the sills.

The parts are assembled by first placing the upper link 30 in position on the spring cage and cylinder, which is done by tilting the link relatively to the cylinder and inserting the T-heads in the pocket formed under the flange 34. The link 30 is then swung to horizontal position. The yoke 25 is placed in position on the supporting angles therefor, after which the friction cylinder and spring cage with the upper link assembled therewith, are inserted through the yoke and the parts moved rearwardly so that the link 30 will rest on the block 11. The follower 24 is then inserted and last the lower link 30 is applied to the cylinder. Finally, the pin 32 is inserted and all the parts are held up in place by the tie plates 35 and 37. The draw bar can be inserted after the other parts have been assembled, as will be understood.

In draft, it is apparent that the spring cage and friction shell will be prevented from forward movement by the links 30 on account of the shouldered connections between said links and the friction shell. The yoke 25, however, moves with the draw bar and thus the friction mechanism will be actuated through said yoke and the follower 24. In buff, the yoke 25 and follower 24

- remain stationary, but the friction shell and spring cage are moved rearwardly by the draw bar, thus actuating the friction mechanism. In the buffing movement, it is apparent that the links 30 are permitted rearward movement on account of the elongated slots 31. It will be obvious that all the strains of buffing and pulling are transmitted to the center sills through the block 11 and at a point which is closely adjacent the body bolster, a desirable result is obtained, since the tendency of the center sills to buckle between the end sill and the body bolster is thereby minimized.
- 15 I claim:
1. In a draft rigging, the combination with draft sills, of a friction mechanism including a friction shell, of an abutment block mounted between and secured to said draft sills and at the rear of the friction mechanism, a draw bar, a horizontal yoke connected to said draw bar and encircling the friction mechanism, a portion of said yoke passing between the rear end of the friction mechanism and said abutment block,

and links detachably connected to said friction shell and to said block to prevent forward movement of the friction shell but permitting rearward movement of the shell.

2. In a draft rigging, the combination with draft sills, of a friction mechanism including a friction shell, of an abutment block mounted between and secured to said draft sills and at the rear of the friction mechanism, a draw bar, a yoke connected to said draw bar and encircling the friction mechanism, and links detachably connected to said friction shell and to the said block to prevent forward movement of the friction shell, but permitting rearward movement of the shell, the yoke being arranged horizontally and said links being also arranged horizontally, one above the other.

In witness that I claim the foregoing I have hereunto subscribed my name this 11th day of July 1916.

GOODRICH Q. LEWIS.
